UNITED STATES PATENT OFFICE.

JOHN R. BLINCK AND CHARLES H. WEST, OF JERSEY CITY, NEW JERSEY.

TELEPHONE SYSTEM.

SPECIFICATION forming part of Letters Patent No. 640,988, dated January 9, 1900.

Application filed May 8, 1899. Serial No. 715,909. (No model.)

To all whom it may concern:

Be it known that we, JOHN R. BLINCK, a subject of the Queen of the Netherlands, and CHARLES H. WEST, a citizen of the United States, both residing in Jersey City, in the county of Hudson and State of New Jersey, have invented an Improvement in Telephone Systems, of which the following is a specification.

10 Our invention relates to telephone systems, and has special reference to the class of telephone systems which are now designated as "party-line" telephone systems—in brief, a system wherein a number of subscribers are 15 carried upon a single line or plurality of lines, which lines usually enter a central station or switching-station, the object being to enable the operator at the central or switching station to call up individual subscribers on the 20 party-line and connect the said subscriber with a subscriber on another or the same party-line and to enable the inactive instruments on the said line or lines to be what we herein term "locked," which term as used 25 by us herein includes any means of rendering the said instruments ineffective to break in upon the line.

We will with the aid of the accompanying drawings describe our invention and one form 30 or embodiment thereof, it being understood that we do not thereby limit ourselves to the construction and arrangement shown, but refer to the claims for a succinct statement of the main characteristics of our invention.

35 In the accompanying drawings we have illustrated in Figure 1 a party-line entering a central or switching station, which party-line is provided with a series of instruments or substations, a convenient number of which 40 is six, although a less or greater number within limits may be connected. In Fig. 2 we have shown the positions assumed by the movable parts of the magnetic circuit affected by the magnetic circuit-controllers at the substations when in their ringing, locking, and 45 unlocking positions, as will be fully described hereinafter. In Fig. 3 we have shown in detail one form of the circuit arrangement of the subscribers' stations, the same representing the circuit arrangement in stations Nos. 50 1, 2, 3, and 4 illustrated in Fig. 1. In Fig. 4 we have shown the circuit arrangement of

the subscriber's station at stations 5 and 6 of Fig. 1. Fig. 5 shows a detail side view of a portion of the controller shown in Fig. 3. Fig. 6 55 shows an end or detail side view thereof. Fig. 7 is a side view of the reversible key employed at central in ringing up a subscriber, the said key being arranged to ring up one party-line without ringing into the calling-subscriber's 60 circuit. Fig. 8 is a sectional detail view of the key shown in Fig. 7, the section being taken on the line 88 of Fig. 7. Fig. 9 is a plan view of the key. Fig. 10 is a detail view of the key detached from its support and 65 shown separately; and Fig. 11 is a table of the polarities employed in ringing, (from central,) locking, and unlocking.

It is not deemed expedient to herein describe in detail the principles upon which the 70 apparatus operates; but in explaining the various parts we will be careful to state the operations performed and the functions of the various circuits.

Referring generally to Fig. 1 of the drawings, the "central" or "switching" station (terms herein employed interchangeably) is represented at A, and B, C, D, E, F, and G indicate the substations or subscribers, which will hereinafter be referred to as Nos. 1 to 6, 80 inclusive, for the purposes of clearer and less redundant description and in accordance with the logical development of the subject.

It will be observed that the substation-circuits, which will be hereinafter fully described with reference to Figs. 3 and 4, are connected across a pair of lines a b, which will hereinafter be referred to together as the party line or lines. The line a is connected to a line a', which enters the central station 90 and is connected with a spring-jack or plug-spring a². The other line b enters the central or switching station by the line b', which is connected to a spring b² of the same spring-jack. The springs a² b² coöperate with terminals a⁴ b⁴, connected to wires a⁸ b⁸, connecting with the calling-drop d, which is grounded through the wire d'. A clearing-out drop d² is likewise connected to the ground-wire d' by a wire d³. Another pair of party-lines 100 e f enter the central or switching station and are connected to the line-springs e' f'. e² f² are the other pair of springs, which coöperate with the line-springs e' f' to constitute the

calling-jack of the other party-line and are connected through wires $e^3 f^3$ with the line-drop g , which is connected by a wire g' with the ground-wire d' . These connections just 5 described constitute the two jacks employed for answering and calling, it being understood that one jack is in one party-line or pair of party-lines and the other jack is in another party-line or pair of party-lines, the 10 ringing-off drop d^2 being common to both plugs.

- H I represent, respectively, the answering and calling plugs for coöperating with the answering and calling jacks. These plugs are 15 each preferably provided with a pair of contacts $h h'$ and $i i'$, respectively. These answering and calling plugs are connected, respectively, with the two sides of the reversible key J. (Shown in Figs. 8 to 10, inclusive.) 20 Fig. 1 should now be read in connection with the said figures. The contact h of the answering-plug H is connected by a wire h^2 with the spring h^3 of the reversible key J. The contact h' is connected, by means of the wire h^4 , 25 with the opposite spring h^5 . These two springs $h^3 h^5$ coöperate with a pair of springs $h^6 h^7$, which are connected by wires $h^9 h^8$ to the corresponding springs $h^{10} h^{11}$ of the opposite side of the reversible key. 30 $h^{12} h^{13}$ are springs which coöperate with the springs $h^3 h^5$ and are connected to the wires $h^{17} h^{18}$, which are connected with the terminals of the calling-off drop d^2 and which are adapted to coöperate with the terminals h^{14} 35 h^{15} of the listening-in key h^{16} , to which the central or station telephone apparatus K is connected. The wires $h^{17} h^{18}$ are connected to springs $h^{19} h^{20}$, which are adapted to coöperate with springs $h^{21} h^{22}$, which are connected 40 to the contacts $i i'$ of the calling-plug I. The two sides of the reversible key J are employed for the purpose of enabling the operator to ring into one party-line or the other without ringing into the line of the calling subscriber. 45 This reversible key, as will be obvious from the circuits, may be employed to talk into either party-line independently without talking into the other party-line. The wires $h^8 h^9$ are connected by the wires $a^5 b^5$ to the contact-springs of an unlocking-key L and to a 50 series of calling-keys 1^a to 6^a , inclusive, whose back contacts are connected, respectively, to the lines $a^6 b^6$, suitable batteries or generators being connected thereto, as indicated by the 55 polarity-signs on Fig. 1. The polarities employed in ringing, locking, and unlocking are as shown in the table of polarities in Fig. 11. One spring of each of the pairs of middle springs in calling-keys $1^a 2^a 3^a 4^a$ is connected 60 to the ground-line G^{10} , so as to ring over a grounded circuit 2, while the middle springs in the calling-keys $5^a 6^a$ are connected across the calling-lines $a^5 b^5$ and the outside springs to battery-wires $a^6 b^6$, so as to ring over a metallic circuit. By this means the proper connections are made for giving the requisite 65 polarities in calling.

The unlocking-key L needs special description. The line a^5 is connected to one of the middle springs i^2 of the unlocking-key, and 70 the other line b^5 is connected to the other middle spring i^3 of the unlocking-key. The outside springs i^4 are connected together to the negative source b^6 . The remaining two springs i^5 are connected together by the wire i^6 and 75 to the ground-wire G^{10} , and are carried upon insulating-blocks i^7 , secured to the springs i^8 , which are both connected to the positive source a^6 .

By following out the circuits it will be obvious 80 that by depressing any one of the keys 1^a to 6^a , respectively, the polarities indicated in the table of polarities, Fig. 11, may be thrown upon one or both of the lines $a b$ and that the unlocking-key will also give its set 85 of polarities, as indicated in the table of polarities. These polarities will produce at the substations the effects which will be mentioned in detail when the said substations are described. 90

The apparatus at the subscribers' stations will now be described, and for this purpose reference should be had more particularly to Figs. 3 and 4. As before stated, in Fig. 3 we have shown in detail the circuit arrangement 95 in subscribers' stations Nos. 1, 2, 3, and 4, and in Fig. 4 the circuit arrangement of subscribers' stations Nos. 5 and 6. These circuit arrangements differ only slightly, the difference in the wiring being necessitated by the fact 100 that the calling or ringing of the subscriber is effected in stations 1, 2, 3, and 4 over one or the other of the lines $a b$ used as a grounded circuit, while in stations 5 and 6 the calling or ringing is effected over the metallic circuit, 105 as will be obvious from the table of polarities in Fig. 11. The locking and unlocking are likewise effected by the employment of both sides of the line, as will be obvious from an inspection of the unlocking-key in Fig. 1 and 110 from the following description:

Referring for the present particularly to Fig. 3, the telephonic receiving and transmitting apparatus is connected to line as follows: The wire o , connected to the line-wire 115 a , leads to one side of the receiver r , and the wire o' leads to the other terminal of the receiver r , the condenser k being interposed. These wires to the receiver are adapted to be short-circuited by the swinging armature m' 120 of the locking-relay m through wires $o^2 o^3$. The station-transmitter t is connected into the primary circuit of the induction-coil T through wires t' , station-battery S B, wire t^2 , telephone-switch s , and wires $t^3 t^4$. The magnetic circuit-controlling magnet or controller p , by which the call or ringing is effected in the subscriber's station, is connected to the line a through the wire o^4 and to the line b by the wire o^5 , the middle point of the winding of the controller being connected to the ground G' (or the ground G^5 in Fig. 4) by the wire o^6 . The action of the controller p is to 125 modify the effect of the permanent-magnet 130

yoke n upon the pivoted bars $n' n^2$, which are pivoted to the terminals $n^3 n^4$ in a manner well understood.

Referring for the moment to Fig. 6, it will be noticed that the pivoted bar n' carries a small leaf-spring n^5 , which makes a rubbing contact with the pole n^6 of the permanent magnet n . The bars $n' n^2$ swing freely in the space between the poles of the electromagnet of the controller and the pole-pieces of the yoke n^7 of the controller, as will be clearly seen by an inspection of Fig. 5, so that the action of the controller-electromagnets is to modify the effect of the permanent-magnet yoke n to produce the swing of the bars, and it is by suitable combinations of polarities transmitted from the central station or switching station that the bars may be thrown into suitable positions to effect the ringing and unlocking of the subscribers' stations, and, as will be presently explained, the locking taking place through the action of a subscriber ringing central.

A diagram of the positions assumed by the armatures of the various stations in ringing, locking, and unlocking is exhibited in Fig. 2, in which x' to x^6 represent the positions of the armatures in the stations 1, 2, 3, 4, 5, and 6, and y' to y^6 the positions of the armatures in locking at the various stations, and z' to z^6 the positions of the armatures in unlocking at the various stations. A bell or other signal-receiving device q is located at the subscriber's station. When a subscriber is called, this bell is rung by the action of the bars $n' n^2$, or one of them, closing the circuit of the bell. The bell-circuits are as follows: As it will be understood, the ringing of the bell is effected by the station-battery S B. From the opposite poles of this battery two wires $o^7 o^8$ lead to the terminals $n^3 n^4$, respectively, to which the bars $n' n^2$ are pivoted. An additional wire o^{10} leads from the wire o^9 of the bell to the front contact o^{50} of the bar n' . The bar n' , as before stated, is provided with a spring n^5 , which makes rubbing contact with the permanent-magnet yoke n , to which yoke one of the terminals of the bell q is connected by the wire o^9 . The other terminal of the bell q is connected by the wire o^{10} with the back contact o^{11} , with which the bar n^2 coöperates, so that the passage of a current of suitable polarity, let us say, over the line b to ground will cause the bar n^2 to strike against the contact o^{11} , as indicated at x' in Fig. 2 and in the table of polarities, Fig. 11, thereby closing the bell-circuit and causing the same to ring. A wire o^{26} leads from the wire o^{10} to the spring l' of the calling-generator switch for a reason presently to be explained. The locking-relay m is connected in circuit in the following manner: One of its terminals m^2 is connected by wire o^{12} to the wire o^{13} , which runs to the back contact o^{27} , which coöperates with the bar n' . The wire o^{13} likewise connects with the wire o^{14} , which is connected to the front contact o^{15} of the bar n^2 . The wire o^{13}

continues onward and is connected to the spring o^{16} , which receives the impact of the spring l' of the substation ringing-generator l , as will be explained. It must be understood that this generator is not necessarily a mechanically-operated device, but may be batteries, &c. The opposite terminal m^3 of the locking-relay is connected by the wire o^{17} with the wire o^{18} , connected to the contact l^2 of the ringing-generator and to the terminal s' of the short-circuiting telephone-switch, the terminal s^2 of the short-circuiting telephone-switch being connected by the wire o^{20} to the wire o^{12} , running to the terminal m^2 of the locking-relay, so that when the telephone-hook is up the locking-relay will be short-circuited. The function of the locking-relay is to short-circuit the telephone transmitting and receiving apparatus and the ringing-generator l , so that when the armature m' of the said locking-relay is set by an impulse or impulses into the positions shown in Figs. 3 and 4 the armature m' of the said locking-relay will short-circuit the telephone apparatus through the wires $o^2 o^3$ and will short-circuit the generator l through wires $o^{21} o^{22}$. The construction of the calling-generator, its circuits, and connection with the lines will now be described. This generator is herein shown as a mechanically-operated continuous-current generator l , one terminal of which is grounded through the wire l^3 and the other terminal of which is connected, through the wire l^4 , to a contact l^5 , which is adapted to coöperate with a line-spring o^{23} , which is connected, through wire o^{24} , to the line a and which is adapted to coöperate with another line spring or wire o^{25} , which is connected to the line b . The subscriber turns the crank l^{10} of the ringing-generator l , thereby swinging the pivoted levers l^6 by the wheel l^7 and pin-and-slot connection l^8 , so as to cause the end l^9 of the lever l^6 to bring the spring o^{25} against the spring o^{23} and the latter against the contact or terminal l^5 , so as to call central through both sides of the line and the ground-wire l^3 , it being remembered that the calling-drop d at the central (see Fig. 1) is connected to both sides of the line through the wires $a' b'$ and grounded through the ground-wire d' . At the same time the spring l' is carried away from contact l^2 and brought into contact with spring o^{16} , thereby completing the bell q circuit locally and opening the circuit of the locking-relay, thereby "blocking" the same to prevent it from being operated by the unlocking apparatus at central.

The construction shown in Fig. 4 is quite similar to that shown in Fig. 3, with the exception that the connections of the contacts of the bars $n' n^2$ are arranged slightly differently, as the calling or ringing is effected from central by the employment of a metallic circuit instead of a grounded circuit, as in Fig. 3, the ground-circuit through the middle of the controller-magnet being preserved for the purpose of locking and unlocking the instruments. A reference to Fig. 11 of the

table of polarities will disclose the fact that both unlocking and locking are effected over a grounded circuit.

In Fig. 4, which, as before stated, illustrates the organization of the station-circuits at sub-stations 5 and 6, the contact o^{50} is connected to the wire o^{12} by the wire o^{28} instead of being connected directly to the bell-terminal by wire o^{40} , as in Fig. 3. The bell is sprung across between the wire o^{10} and the contact o^{27} through wires o^{29} and o^{30} .

It now remains to describe the construction of the reversible key J. For this purpose reference is to be had to Figs. 7 to 10, inclusive. In these figures the key J is shown as pivoted by a shaft j in a bearing j^{12} . The key J is provided with a plurality of oppositely-placed cams j^2 , j^3 , which act upon plungers j^4 , j^5 to depress either one or the other, accordingly as the key is swung to one side or the other to engage one or the other of its cams with the appropriate plunger.

The detailed operation of the system is as follows: We will describe a complete operation whereby the central is called up, and a connection between the station shown in Fig. 3 of the drawings is effected with the station shown in Fig. 4 of the drawings by means of the central. The station represented in Fig. 30 will be designated "Station 1," and the station represented in Fig. 4 will be designated "Station 5." The party at station 1, seizing the handle l^{10} , sets the generator in action, brings the contact-springs o^{23} , o^{25} together, separates l' from l^2 , and brings l' in contact with spring o^{16} . As one side of the calling-generator is grounded at l^3 , the current passes through wire l' to l^2 and thence through o^{23} , o^{25} to the lines a and b . Part of the current traverses the lines a , b to the central station, where it operates the calling-drop d . Part of the current likewise passes through wire o^4 and through a spool of one of the controller-magnets to the ground at o^6 , and another part of the current passes by wire o^5 through the spool of the other controller-magnet to the ground at o^6 . These currents will actuate the bars n' , n^2 , so that they will assume the position shown at y' in Fig. 2, it being understood that calling the central station will effect the locking of the other instruments on the line. If y' of Fig. 2 be kept in mind, the circuits in Fig. 3 may be traced as follows: from the positive pole of the station-battery S B by wire o^7 to n^3 , thence by n' to o^{50} , thence by o^{40} to the bell-terminal, through the bell, thence by wire o^{28} to the spring l' , which is in contact with spring o^{16} , through which the current passes to wire o^{13} , thence by wire o^{14} to the back contact o^{15} of the bar n^2 , and thence by wire o^8 to the negative pole of the battery. It will be observed that this current will ring the bell q —that is to say, the calling-subscriber rings his own bell, as well as throws the drop at the central. He does not, however, actuate his own locking-relay, for the said locking-relay, although it is connected

to wire o^{12} , has its circuit broken at l' and l^2 . It will consequently remain inactive; but it is to be noted, however, that in ringing the relay 70 is not in the position shown in Figs. 3 or 4, but in an intermediate position. The relay is shown in Figs. 3 and 4 in its short-circuiting position for the purposes of clearer illustration.

Having observed the effect of the calling-current at the subscriber's station, let us pass to the other stations on the line, using the station shown in Fig. 4 as an example. This station being the fifth station on the line, we 80 turn to Fig. 2 and observe the position assumed by the bars at y^5 in order to aid us in tracing the circuit. The currents enter through lines a , b by wires o^4 and o^5 , actuate the controller-magnets, and go to ground at 85 G^5 , thus throwing the armatures into the position shown at y^5 in Fig. 2. Commencing at the positive pole of the battery, the circuit may be traced as follows: by wire o^7 to n^3 , thence by n' to o^{50} , thence by o^{28} to o^{12} , through 90 o^{12} to m^2 , through the locking-relay by wires o^{17} , o^{18} to l^2 , thence by l' , wire o^{26} , back contact o^{11} , bar n^2 , n^4 , and wire o^8 to the negative pole of the battery. It will be observed that the current in this instance does not pass 95 through the bell q , but actuates the locking-relay to throw it into the position shown in Fig. 4, so as to lock this station. The same thing happens at all the other stations on the line except the calling-station, as the relay-circuit at this station is open at l^2 . Station No. 1 now asks the central to connect him with No. 5. Thereupon the central throws down her unlocking-key and unlocks the entire line. The unlocking-circuits will be 100 traced in Fig. 3. Turning to Fig. 2, at z' we get the positions of the bars n' , n^2 as the central sends a negative current over both sides of the line to unlock. Starting from the positive pole of the battery, the current passes by 105 wire o^7 , bracket n^3 , bar n' , wire o^{13} , wire o^{12} , locking-relay m , wires o^{17} , o^{18} , contact l^2 , spring l' , wire o^{26} , wire o^{10} , bar n^2 , and wire o^8 to the negative pole of the battery. In Fig. 4 the same unlocking-current passes, the movable 110 bars being in the positions z^5 in Fig. 2. The local unlocking-circuit is as follows: by wire o^7 , bracket n^3 , movable bar n' , wire o^{30} , bell q , wires o^{29} , o^{26} , spring l' , contact l^2 , wire o^{18} , wire o^{17} , locking-relay m , wire o^{12} , wire o^{13} , wire o^{14} , 115 bar n^2 , and wire o^8 to the negative pole of the station-battery. This is effective to unlock the station; but it is to be observed that the bell q does not ring, for the reason that by the position assumed by the movable bars n^4 , n^2 it is in series with the locking-relay m , and as the locking-relay has a resistance of some forty or fifty ohms and the bell a resistance of but in the neighborhood of five ohms the locking-relay alone will be actuated. Having 120 unlocked the line, the central now proceeds to call up the station shown in Fig. 4. This she does by sending a negative current over line a and a positive current over line b , the

ground being neutral. This has the effect of throwing the movable bars n' n^2 into the positions shown at x^5 in Fig. 2. The local circuit will then be as follows: by wire o^7 , bracket n^3 , bar n' , contact o^{27} , wire o^{30} , bell q , wire o^{29} , wire o^{10} , bar n^2 , and wire o^8 to the negative pole of the battery. The parties thus connected may converse immediately, or, if they desire, either may by use of the ringing-generator lock out all the other instruments on the line except the two who are talking, their relays being now short-circuited through the receiver-telephone hook. When the two on the same party-line have finished their conversation, either may ring off with his ringing-generator, the signal being received on the clearing-out drop d^2 at the switching-station, whereupon the operator at the central or switching station depresses the unlatching-switch to unlock the line and restore the apparatus to its normal condition.

Having described our invention, what we claim, and desire to secure by Letters Patent, is—

1. In a selective signaling system, the combination of substations located along a double-conductor main line, a magnetic circuit located at each substation and having a plurality of independently-movable elements, a local signaling device at each substation in a circuit responsive to a change in the position of a movable part or parts of the magnetic circuit and electromagnets each responsive to a current sent over one side of the line and governing the action of one of the said movable elements, and a central or switching station provided with signaling means sending particular currents or current combinations for selectively signaling the substations.

2. In a selective signaling system, the combination of a series of substations and a central station, a metallic or double-conductor main circuit, a ground connection at each substation normally in circuit with both sides of the line and means under the control of the subscriber at each substation for transmitting current over both sides of the circuit, locking or short-circuiting means at each substation responsive thereto and means for preventing the locking or short-circuiting means at the stations in use for talking, from being operated by such current.

3. In a signaling system of the character described, the combination of a series of substations in electrical connection, with a double-conductor main line or circuit, a ground-circuit at each substation normally connected to both sides of the line, means at each substation for signaling the same from the switching-station by a particular current or current combination for each substation, means located at each substation for locking or short-circuiting the other subscribers' stations and means at each substation under the control of the subscriber for rendering the locking or short-circuiting device of his station inoperative when a call is desired to be sent to

the central whereby his own instrument will not be locked out when he signals central.

4. In a signaling system of the character described, the combination of a series of substations in electrical connection with both sides of a double-conductor main line or circuit with selective signaling apparatus substantially as described located at the central and substations; a ground-circuit permanently connected to both sides of the line, a locking-relay located at each substation, and circuit connections with the said locking-relay combined with means for manipulating the circuit of the said locking-relay by the transmission of a call from a substation to central to render the said locking-relay inoperative to lock the calling-subscriber's substation.

5. The combination, in a signaling system, of a series of substations in electrical connection with a double-conductor main circuit with selective signaling apparatus substantially as described located at the central and sub stations, a locking-relay located at each substation, a calling-generator at each substation and movable means for automatically connecting the calling-generator with both sides of the line and for also opening the circuit of the locking-relay at the substation where the calling-generator is operated.

6. An electrical signaling system comprising a metallic or double-conductor main line or circuit extending between a central or switching station and a number of substations, a signal-receiving device in a local circuit at each substation, a normally-magnetized loop or yoke of magnetic material constituting a magnetic circuit and a plurality of electromagnetic means connected one to each side of the line at the substation separate and distinct from the said magnetic circuit and adapted to control the same, means for thereby actuating the signal-receiving device, an earth conductor normally in circuit with both sides of the line and a series of signal-transmitting devices at a central or switching station for sending currents to effect the proper change in the devices for manipulating the magnetic circuit at the respective substations so that the receiving device of the substation represented by such signal device and no other is responsive, substantially as described.

7. In a selective signaling system, the combination of a series of substations having individual locking apparatus and a central station, means at each substation for operating the locking apparatus of the other stations on the line, means at the central station for unlocking the line and means at each substation for "blocking" its locking apparatus when a call has been sent from that substation so that the unlocking apparatus at the central station is inoperative to operate the locking apparatus at the said substation.

8. In a signaling system of the character described, the combination of a series of sub-

stations in electrical connection with a double-conductor main circuit, and having individual locking apparatus, means at each substation for receiving signals from the switching-station by particular current or current combinations for the substations, means at each substation for operating the locking apparatus of the other stations on the line, means at the central station for unlocking the line and means at each substation for "blocking" its locking apparatus when a call has been sent from that substation so that the unlocking apparatus at the central station is inoperative to operate the locking apparatus at the said substation.

9. In a selective signaling system, the combination of a series of substations having in-

dividual locking apparatuses comprised in part by an electromagnet and a central station, means at each substation for operating the locking apparatus of the other stations on the line, means at the central station for unlocking the line, and means at each substation for manipulating the circuit of its electromagnet forming part of the locking apparatus so that the unlocking apparatus at the central station is inoperative to operate the locking apparatus at the said substation.
